UNITED STATES PATENT OFFICE.

GILBERT L. CROWELL, JR., OF ARLINGTON, NEW JERSEY, ASSIGNOR TO
DOMINICK & HAFF, OF NEW YORK, N. Y.

DESIGN FOR A BACK FOR BRUSHES, &c.

SPECIFICATION forming part of Design No. 24,919, dated November 26, 1895.

Application filed October 5, 1895. Serial No. 564,810. Term of patent 14 years.

To all whom it may concern:

Be it known that I, GILBERT L. CROWELL, Jr., a citizen of the United States, residing at Arlington, in the county of Hudson and State 5 of New Jersey, have invented and produced a new and original Design for the Backs of Brushes, Mirrors, and other Articles, of which the following is a description, reference being had to the accompanying drawing, which 10 illustrates the design.

The drawing shows a representation of the back of a brush and handle thereof ornamented with my design.

The general outline of the brush is of ovate 15 form. On the upper portion of the brush-back is the representation of the head of a satyr A, flanked by designs of fruit B and conventionalized leaves C. At the lower end of the back is the shield D, supported by the 20 heraldic lion-head figures E and embellishment of scrollwork F.

The outline of the handle of the back is spatulate, and at the lower end thereof is the scrollwork G, supporting the series of conventionalized lotus flowers H, which gradually diminish in size in conformity with the outline of the handle. 25

The essentials of design of the back of the brush are the satyr-head, the shield-like figure, and the heraldic devices of lion-heads. 30

The essential features of design of the handle consist of the scroll figure of the lower portion thereof and the series of lotus flowers.

What is claimed as new is—
The design for the back of a brush, mirror 35 or similar article, substantially as shown and described.

GILBERT L. CROWELL, JR.
